UNITED STATES PATENT OFFICE.

JOHN FREDERIC KUBLY, OF NEW YORK, N. Y., AND CHARLES FREDERIC CRAILSHEIM, OF PARIS, FRANCE.

IMPROVEMENT IN BOTTLES FOR GASEOUS LIQUIDS.

Specification forming part of Letters Patent No. 101,889, dated April 12, 1870.

To all whom it may concern:

Be it known that we, JOHN FREDERIC KUBLY, of the city and State of New York, and CHARLES FREDERIC CRAILSHEIM, of Paris, in the Empire of France, have invented and made a new and useful Improvement in Bottles for Wines, Champagne, &c.; and we do hereby declare the following to be a full, clear, and exact description of the said invention, reference being had to the annexed drawings, making part of this specification, wherein—

Figure 1 is a vertical section of a bottle fitted with our improvements. Fig. 2 is a plan of the stopper as turned back, and Fig. 3 represents the halves of the divided screw-neck-band.

Similar marks of reference denote the same parts.

Our invention is designed for excluding the atmosphere and confining the contents of the bottle, but allowing said contents to be drawn off in detail or emptied at once.

This invention consists in a bottle for effervescent liquids, formed with a side neck and tube descending to near the bottom of the bottle, to which a valve is applied, so that the liquid may be drawn off in detail without opening the bottle, in combination with the neck at the top and a stopper applied thereto, so that the bottle can be filled through this last-named neck or the remaining portions of the contents be emptied therefrom.

In the drawings, *a* is the bottle, *b* a neck at the top of the bottle, and *c* a neck at the side of the bottle, forming a branch. These are all made in glass.

d is a neckband, made in two parts, with projecting pins entering corresponding holes, as seen in Fig. 3, by which the parts will be held together; and around the outside of the band a screw-thread is formed. This band is to fit the neck *b* or *c*, and upon it is screwed the socket *e* or *f*.

The socket *e* is in the form of a hollow band, within which is a ring, *h*, which can be partially revolved by a thumb-piece, *g*, that projects through a slot in *e*, and on the outside of this ring *h* is a projecting inclined flange, that forms a cam to act upon the hooked catch *k* of the stopper *l* and draw said stopper firmly

down upon the end of the neck or mouth of the bottle. The stopper *l* is hinged to the socket *e* at *i*, and within said stopper *l* is an elastic plug, *m*, of india-rubber, that sits within the mouth and bears upon the end of the bottle.

A tube, *n*, is provided, that passes through the neck *c* nearly to the bottom of the bottle, and this tube *n* has a flange, *n'*, that sits within a recess in the socket *f*; and *2* is a disk or washer of india-rubber between *n'* and the face of the neck *e*, that makes the parts tight.

At the front of the socket *f* is a valve, formed so as to be introduced within the tube *o*. This tube *o* receives the stem *r* of the valve *s*, and this stem *r* extends to the cap *t*.

At *u* is a spring to keep the valve *s* to the seat *v*, and at *3* there are disks of rubber supported between metal disks, so as to make a perfectly-tight packing around the stem *r*. The valve *s* is formed hollow to receive an elastic washer, and the seat *v* is made tubular to press on the same and form a tight joint.

A small nozzle, *w*, is screwed into the end of the tube *o*, to give direction to the liquid as it escapes in small quantities when the cap or compression-head *t* is forced down.

This device allows the wine or other liquid to be drawn in small quantities, and at the same time excludes the atmosphere. The bottle is to be filled at the neck *b*; or its contents may be emptied therefrom, if desired.

What we claim, and desire to secure by Letters Patent, is—

The side neck, *c*, tube *n*, and valve *s*, constructed and applied substantially as set forth, in combination with the neck *b* and stopper *l*, as and for the purposes set forth.

In witness whereof we have hereunto set our signatures in the presence of the subscribing witnesses.

JOHN FREDERIC KUBLY.

CHARLES FREDERIC CRAILSHEIM.
